UNITED STATES PATENT OFFICE

150,081

DESIGN FOR A COMBINED CLOCK CASE AND PICTURE FRAME

Frank P. Mandel, Chicago, Ill.

Application November 8, 1947, Serial No. 142,405

Term of patent 7 years

(Cl. D42—7)

To all whom it may concern:

Be it known that I, Frank P. Mandel, a citizen of the United States, residing at Chicago, in the county of Cook and State of Illinois, have invented a new, original, and ornamental Design for Combined Clock Case and Picture Frame, of which the following is a specification, reference being had to the accompanying drawings, forming a part thereof in which:

The essential features of my design are shown in full lines, the broken lines shown being for illustrative purposes only.

I claim:

The ornamental design for a combined clock case and picture frame, substantially as shown and described.

FRANK P. MANDEL.
